UNITED STATES PATENT OFFICE

149,758

DESIGN FOR A MEDALLION OR SIMILAR ARTICLE

Thomas H. Jones, Washington, D. C., assignor to the United States of America as represented by the Secretary of War

Application January 23, 1947, Serial No. 136,335

Term of patent 14 years

(Cl. D29—19)

To all whom it may concern:

Be it known that I, Thomas H. Jones, a citizen of the United States and resident of the city of Washington in the District of Columbia, have invented a new, original, and ornamental Design for a Medallion or Similar Article, of which the following is a specification, reference being had to the accompanying drawings, forming a part thereof.

Fig. 1 is a front view of a Medallion, showing my new design.

Fig. 2 is a side view of the same.

It is understood that my design may be embodied in such articles as a medal, badge, plaque, or sign, without departing from the spirit of my invention.

The essential features of my design are shown in full lines.

I claim:

The ornamental design for a medallion or similar article, as shown and described.

THOMAS H. JONES.
